UNITED STATES PATENT OFFICE.

CHARLES JACKSON, OF BIRMINGHAM, ENGLAND.

FASTENING TO BE USED AS SLEEVE-LINKS, &c.

SPECIFICATION forming part of Letters Patent No. 459,469, dated September 15, 1891.

Application filed February 24, 1891. Serial No. 382,545. (No model.) Patented in England October 13, 1887, No. 13,910, and September 7, 1888, No. 12,962.

To all whom it may concern:

Be it known that I, CHARLES JACKSON, engineer, a subject of the Queen of Great Britain, residing at 224 Herbert Road, Birmingham, England, have invented certain new and useful Improvements in Fastenings to be Used as Sleeve-Links and for other Purposes, (for which I have obtained Letters Patent in Great Britain, No. 13,910, dated October 13, 1887, and No. 12,962, dated September 7, 1888,) of which the following is a specification.

This invention has for its object improvements in fastenings to be used as sleeve-links and for other purposes. I construct such fastenings with two spring flaps or clasps, and these are so arranged that one flap or clasp may be passed through a button-hole, say, on one side of the sleeve of a shirt and closed down upon the fabric, thereby securing the fastening to it, and another flap or clasp may afterward be passed through another button-hole on the other side of the sleeve and then closed down, thereby separately attaching the fastening to the second of the two thicknesses of fabric which the fastening is used to connect. In some cases I provide more than two spring flaps or clasps with a view to rendering the attachment more secure.

In order that my said invention may be fully understood and readily carried into effect, I will proceed to describe the drawings hereunto annexed.

In the drawings, Figure 1 is a side elevation of a fastening or sleeve-link constructed in accordance with my invention. It is drawn larger than it would usually be constructed. Fig. 2 is also a side elevation, but with the parts in another position. Fig. 3 is an under side view. Fig. 4 is a section on the line 4 4 in Fig. 3. Fig. 5 is a section on the line 5 5 in Fig. 3. Fig. 6 is a section on the line 6 6 in Fig. 3. Figs. 7, 8, and 9 show separately some of the parts. Fig. 10 is an under side view with the outer or casing plate removed. Fig. 11 shows a modification. Fig. 12 is a plan of a fastening similar to that shown by the preceding figures, but differing somewhat in the detail of its construction. Fig. 13 is an elevation. Fig. 14 is a section, and Fig. 15 is an under side view, of the fastening shown by Fig. 12. Fig. 16 is a side elevation in which

two flaps or clasps only are provided. Fig. 17 is a plan, and Fig. 18 is a longitudinal section, of the fastening shown by Fig. 16. Fig. 19 is a side elevation, and Fig. 20 is a plan, of another fastening similar to that shown by Figs. 16, 17, and 18, but somewhat different in form. Fig. 21 is a section of the fastening shown by Figs. 19 and 20. Fig. 22 is a plan of the foundation-plate, and Fig. 23 is a section on the line x x of Fig. 22.

a is a disk or plate of metal serving as the foundation on which the movable parts are mounted. These consist of two flaps or clasps b and c and a flap or clasp d. The flap b is shown separately by Fig. 7 and the flap c by Fig. 8. In place, however, of the flaps crossing each other, they may be constructed as shown in Fig. 11.

Fig. 9 shows the flap or clasp d. The flaps b and c, as will be seen, are formed with pivots, and these fit into indentations or recesses in the foundation-plate a. They are kept in place by a cover-plate e, and this is secured by the ears a' a' of the foundation-plate a, which are turned over upon it. The same cover-plate serves to hold the spring f in such a position that it presses upon square shoulders formed upon the flaps b and c, so that the spring tends to bring the flaps when they are raised to the position in which they are shown in Fig. 2, where they stand up approximately at right angles to their former position. The flaps b and c are also geared together by teeth, as the drawings indicate, so that they move up and down together. The flap or clasp d is furnished with pivots, and these are held in small lugs a² a², projecting up from the foundation-plate. The flap or clasp is continued beyond the pivots and comes into contact with a spring g, which is attached to the dished head-plate or casing h of the fastening. The casing h is secured to the foundation-plate a by bending or burring its edges, as indicated in Fig. 6. In the use of this link or fastening one lappet or thickness of the fabric is laid over the flaps b and c while they stand in the position indicated in Fig. 2, the said flaps passing through a hole suitably formed in the fabric to receive them. The flaps b and c are then closed down upon the fabric, and so the link or fastening be-

comes securely attached to it. The second lappet or thickness of fabric, which is to be held to the first by means of the link or fastening, is now laid over the flap or clasp *d*, this passing through a hole in the fabric suitably formed to receive it. The flap or clasp *d* is then shut down, so that now the parts of the link or fastening occupy the positions in which they are represented in Figs. 3, 4, 5, 10 and 6.

The fastening represented by Figs. 12 to 15 is of simpler construction than the preceding, but similar in its action. It consists of a dished plate *i*, provided on its convex face with lugs, to which the pair of transverse flaps or clasps *k k* are pivoted, and also a third flap or clasp *l*, which folds down over the pair. A spring-plate *m*, of a form clearly shown in Fig. 15, serves for all the flaps or clasps to hold them either in the folded position or when standing erect. The spring-plate *m* is attached to the plate *i* by rivets or otherwise.

Sometimes for the sake of simplicity I provide two flaps or clasps only. Figs. 16, 17, and 18 represent such a fastening. *A* is a plate which is dished, as shown, to receive the cover *B*, the two being attached together by rubbing or otherwise. *C* and *D* are two spring flaps or clips pivoted to lugs *C' D'*, fixed to the plate *A*. The tail ends of the flaps or clips *C* and *D* bear against the ends of the flat spring *E*, whose middle is riveted at *F* to the plate *A*.

Figs. 19 to 23 show a fastening of another form. As shown in Figs. 22 and 23, the portions *A' A'* of the foundation-plate are turned

up, forming lugs to receive the axes of the spring flaps or clips *C* and *D*. The flap or clip *C* is forked, (see Fig. 20,) the flap or clip *D* lying between the arms of the fork. This construction admits of the hinges of the flaps or clips being closer together than in the construction shown in Figs. 16 to 18. The tail ends of the flaps or clips *C* and *D* rest upon the ends of the spring *E*, which is riveted at 45 *F* to the plate *A*, as shown in Fig. 21.

What I claim is—

1. A sleeve link or fastening consisting of a plate *i*, three spring-flaps *k k* and *l*, pivoted to lugs on the plate *i*, and a spring *m*, operating upon all the said flaps to retain them either in the open or closed position, substantially as described.

2. A sleeve link or fastening consisting of a plate and three spring-flaps, two of which are connected to the plate by parallel pivots and the other of which is arranged on a pivot transverse to the pivots of the other two flaps, for the purpose specified.

3. A sleeve link or fastening consisting of the combination of a plate, a spring-flap pivoted to the plate, another spring-flap pivoted to the same side of the plate, but at another part thereof, both of said flaps being constructed and adapted to fold down and separately hold two parts of the fabric to the link or fastening, substantially as set forth.

CHARLES JACKSON.
